APPARATUS FOR LAUNCHING ROCKET-PROPELLED SHELLS

George Rasmussen, Long Beach, and Robert J. Spellmire, San Marino, Calif., assignors, by mesne assignments, to Pike Corporation of America, Los Angeles, Calif., a corporation of California

Filed Feb. 3, 1967, Ser. No. 613,899
2 Claims. (Cl. 89—1.812)

ABSTRACT OF THE DISCLOSURE

An apparatus for launching a rocket-propelled shell which comprises a hollow tube into which a shell is inserted at one end and in which a firing pin is mounted on the other end. The end of the tube adjacent the firing mechanism has at least one pair of flexible but resilient finger elements extending downwardly from the rib structure to hold and detain the lower end of a shell and to hold it into position prior to firing. The shell firing mechanism includes a spring loaded firing pin for striking the shell and means for constraining the firing pin against the action of its spring. The shell firing mechanism also includes a safety device including a spring loaded release pin mounted on a slidable plate.

The present invention relates to rocket launching devices in general and more particularly relates to a launcher mechanism for use with relatively small rocket-propelled shells.

The concepts relating to rockets and rocket launchers are not scientifically new. However, in the past, the rockets and the means for launching these rockets have been relatively large and complex structures. Stated differently, there has not heretofore been a rocket launcher that could easily be held in the palm of one hand and, suitably oriented, fired with the other hand. As may be expected, such launchers would be applicable wherever it would be useful or advantageous to fire small rocket-propelled shells.

It is, therefore, an object of the present invention to provide a launcher mechanism for very small rocket-propelled shells.

It is another object of the present invention to provide an extremely light, compact and inexpensive rocket-launching mechanism.

It is a further object of the present invention to provide a rocket-launching mechanism that can fit into the palm of one hand and fired with the other hand.

The novel features which are believed to be characteristic of the invention, both as to its organization and method of operation, together with further objects and advantages thereof, will be better understood from the following description considered in connection with the accompanying drawings in which an embodiment of the invention is illustrated by way of example. It is to be expressly understood, however, that the drawings are for the purpose of illustration and description only and are not intended as a definition of the limits of the invention.

FIGURE 1 is a side view of a launcher mechanism according to the present invention, the broken-line outline of a shell also being shown to illustrate the mounting of a shell therein;

FIGURE 2(a) is a top view of a launcher mechanism according to the present invention;

FIGURE 2(b) is a side view, in cross-section, of a launcher mechanism according to the present invention showing the internal structural arrangement thereof;

FIGURE 3 is a perspective view of the firing section of

a launcher mechanism according to the present invention; and

FIGURE 4 is a side view of the launcher mechanism illustrating a modification thereof to facilitate its handling and firing.

Considering now the drawings, wherein like or similar parts or elements are given like or similar designations throughout the several figures, reference is initially made to FIG. 1 wherein a side view of a launcher mechanism is shown, the outline of a shell also being shown by means of a broken line to indicate how a shell is mounted in the launcher for firing purposes. The launcher mechanism is designated 10 and the shell illustratively shown therein is designated 11. It is thus seen that the launcher is basically a hollow tube and that the shell is mounted in the upper portion of it, the means by which the shell is fired being located at the base of the launcher which, in the figure, is at the right end of the tube. It should be noted that to hold the shell in place, there is a groove 11a located at the base of the shell which cooperates with certain elements of the launcher, and the manner in which the groove aids in this respect will be explained more fully below.

The firing means shown in FIG. 1 includes a plate type key 12, made of metal or other sturdy material, to which a string 13 is attached and it is the pulling of this string that initiates the firing of a shell 11. Key 12 is fitted or mounted in a slot or key way 14 in the wall of the launcher mechanism and when string 13 is pulled with sufficient force, the key comes out of this opening to thereby allow the internal portions of the firing apparatus to operate. Finally, it will be noted from FIG. 1 that at the base of the launcher mechanism there is another opening 15 in the wall thereof that intersects key way 14, the function and purpose of this second opening to become clearer later.

A more complete understanding of the construction and operation of a launcher mechanism according to the present invention may be had from FIGS. 2(a), 2(b) and 3 to which reference is now made. As shown therein, the launcher is a tubular or cylindrically-shaped device whose upper portion, which is the portion above the firing mechanism, is hollow to receive a shell. The inside surface of this upper hollow portion is ribbed, there preferably being six ribs equally spaced around the periphery of the tube. The ribs are designated 16 and they extend down into the hollow portion, that is to say, longitudinally along the tube until they end just above the firing structure. The purposes of these ribs are, first, to provide structural strength for the launcher and, second, to reduce the air drag on a shell as it leaves the tube after it is fired, this being achieved because the ribs provide the right kind of spacing between the shell and the wall of the launcher tube.

Also mounted in this hollow portion of the launcher mechanism, at the base of ribs 16 and extending from them in the direction of the firing structure, are a plurality of finger elements 17, there preferably being four such finger elements equidistantly spaced, that is to say, ninety degrees apart, around the periphery of the tube. These finger elements are of flexible and resilient construction and they are intended to and do enter the groove 11a of a shell 11 when one is mounted inside launcher 10, the finger elements thereby holding the shell in place after firing until sufficient thrust has been built up or generated to properly launch the shell, thereby enhancing the stability and accuracy of the rocket. When firing does take place, the forward thrust and initial motion of the shell forces these finger elements to snap out of the groove, thereby releasing the shell from any impediment to its forward motion. Prior to firing, these same finger

elements prevent the shell from falling out of the tube should it be held with its muzzle downward.

Looking now to the bottom portion of the launcher tube, that is to say, to that portion of it that contains the firing mechanism, it can be seen from FIGS. 2(a), 2(b) and 3 that this bottom structure includes a centrally disposed cylindrical chamber 18 in which a spring-loaded firing pin is axially located, the pin being designated 19 and its associated spring being designated 20. As can be seen from FIGS. 2(a) and 3, chamber 18, which is structurally supported by means of radial ribs 21, has a pair of slits 22a and 22b extending transversely through its wall, both slits being in alignment with opening 14 through the launcher wall. Plate or key 12 extends through both these slits to the other side of the chamber, as shown in the figures.

As can be seen more clearly from FIGS. 2(a) and 3, the forward portion of plate or key 12 is generally U-shaped, the opening or spacing between the arms of the U, designated 23, being narrow enough to prevent the firing pin from rushing forward to strike the shell that might be in the launcher tube at the time. In short, key 12 is a release mechanism that releases the firing pin from its restrained position only when the key is withdrawn from slits 22a and 22b. As previously mentioned, this is accomplished when the user pulls on string 13.

Finally, in order to prevent any premature firing or operation of the firing mechanism, the firing mechanism also includes a safety device that prevents the key 12 from being pulled out until the user is ready to do so. More specifically, this safety device comprises a spring-loaded pin or similar type element that is mounted perpendicularly to key 12 in an opening therethrough located in the area between slit 22a and opening 15, as is shown in FIGS. 2(a) and 3. The pin is designated 24 and the spring thereon is designated 25, the pin, because of the spring, normally being in a fully upright or extended position above the key, with the result that normally the pin will not clear or pass through opening 15. This means that pin 24 is long enough so that in its normally extended position it will abut against the wall of the launcher tube above opening 15 and thereby prevent the key from being pulled out. This will, in turn, prevent the release of firing pin 19.

Pin 24 may be held on key 12 by means of a C-washer or clamp located on the other side of the key and, therefore, not shown in the figures because of their particular orientation or perspective. Suffice it to say that when a shell is seated in the launcher tube, such as is illustrated in FIG. 1, the bottom surface of the shell contacts pin 24 and depresses it against the action of its spring 25. Accordingly, only with a shell in position does the pin clear or pass through opening 15 to permit complete withdrawal of key 12 and if string 13 is pulled at this point, the firing pin 19 will strike the shell to fire it into the atmosphere.

Although the use of a string 13 is both effective and economical, it may nevertheless be desirable to modify the launcher mechanism in the manner shown in FIG. 4 wherein a substitute for the string is illustrated. This substitute structure is in the form of a handle 26 that is fastened to the launcher tube by means of a pair of bands or loops 27a and 27b that encircle the tube. The substitute device also includes a member 28 that is rotatably mounted around a bolt 29 as a pivot point, the bolt going through both handle 26 and member 28 at one end thereof. At the other end of the member 28, there is located a pin or prong 29 that is integral with and extends from this member toward key 12, the tip or end of this prong 29 being inserted in or passing through an opening located near the end of the key. Consequently, when handle 26 and member 28 are grasped and squeezed, member 28 rotates about bolt 29, with the result that key 12 is pulled outward by the prong 29 to thereby sufficiently withdraw the key from the firing mechanism to

permit the firing pin 19 to function. For convenience in handling, it will be noted that member 28 has been contoured to conform to the shape of the fingers.

In mounting this substitute arrangement, bands 27a and 27b are initially in a loosened condition so that both of them can be easily slipped onto the launcher tube. When this is done, prong 29 is then slipped into the opening through key 12 and the bands tightened. The device is now ready for use.

One of the advantages of this substitute apparatus over the string 13 is that it provides positive means by which the launcher mechanism can be held with one hand. Furthermore, it provides the user with the enhanced opportunity of orienting the tube in the desired direction and maintaining it steady in that direction. In addition, and more significantly, it affords the user the opportunity both of holding the launcher and firing it with but one hand.

Although a particular arrangement of the invention has been illustrated above by way of example, it is not intended that the invention be limited thereto. Accordingly, the invention should be considered to include any and all modifications, alterations or equivalent arrangements falling within the scope of the annexed claims.

Having thus described the invention, what is claimed is:

1. Apparatus for launching a rocket propelled shell, said apparatus comprising:

a hollow tube into which a shell is inserted at one end and in which a shell firing mechanism is mounted on the other end, the portion of the tube holding the shell having a plurality of rib structures spaced around the inside surface thereof that extends longitudinally along the tube for substantially the length of the shell, said rib structures adding rigidity to the tube and spacing the shell therefrom to minimize air drag thereon when the shell is propelled forward;

said portion of the tube further having at least one pair of flexible and resilient finger elements extending downwardly from said rib structures to grab the lower end of the shell and firmly hold it in place inside said tube prior to firing;

said shell firing mechanism includes a safety device that comprises an opening through the wall of the tube, a plate for activating said firing mechanism slidably mounted in said opening and a spring loaded release pin mounted on said plate perpendicularly thereto, said release pin being too long to pass through said opening unless depressed by a shell in the tube.

2. Apparatus for launching a rocket propelled shell, said apparatus comprising:

a hollow tube into which a shell is inserted at one end and in which a shell firing mechanism is mounted on the other end;

the portion of the tube holding the shell having a plurality of rib structures spaced around the inside surface thereof that extends longitudinally along the tube for substantially the length of the shell, said rib structures adding rigidity to the tube and spacing the shell therefrom to minimize air drag thereon when the shell is propelled forward;

said portion of the tube further having at least one pair of flexible and resilient finger elements extending downwardly from said rib structures to grab the lower end of the shell and firmly hold it in place inside said tube prior to firing; and

said shell firing mechanism including a hollow cylindrically-shaped structure mounted within said tube and oriented along the axis thereof, said structure having a pair of slits through its wall on opposite sides thereof; a spring-loaded firing pin mounted along the axis of said structure; a generally U-shaped plate for activating said firing pin slidably mounted on said structure through the slits thereof,

the spacing between the arms of said U being narrow enough to prevent said firing pin from passing therethrough; and a safety device that prevents said plate being withdrawn from said tube until there is a shell therein, said device including an opening through the wall of the tube whereat said plate is located and through which said plate is slideable, and a spring-loaded release pin mounted on said plate perpendicularly thereto, said release pin being too long to pass through said opening unless depressed by a shell in the tube.
